(57) CLAIM

The ornamental design for a cassette as shown and described.

DESCRIPTION

This Design Patent Application is related to the following commonly owned applications: U.S. patent application Ser. No. 17/889,367, entitled "Cassette for Dispensing Pleated Tubing" filed Aug. 16, 2022; U.S. patent application Ser. No. 16/542,015, entitled "Cassette for Dispensing Pleated Tubing" filed Oct. 4, 2019, now U.S. Pat. No. 11,130,628; and U.S. patent application Ser. No. 14/736,192, entitled "Cassette for Dispensing Pleated Tubing" filed Jun. 10, 2015, now U.S. Pat. No. 10,486,925.

FIG. 1 is a top perspective view of a cassette showing my new design;

FIG. 2 is a lower perspective view thereof;

FIG. 3 is a top view thereof;

FIG. 4 is a bottom view thereof;

FIG. 5 is a front view thereof, the rear side being a mirror image thereof; and,

FIG. 6 is a left side view thereof, the right side being a mirror image thereof.

The broken lines indicate elements which do not form part of the claim herein.

1 Claim, 5 Drawing Sheets
